(57) **CLAIM**

The ornamental design for a rail for conveyor machine, as
shown and described.

DESCRIPTION

FIG. 1 is a front elevation view of a rail for conveyor
machine showing our new design in accordance with a first
embodiment of the present invention;

FIG. 2 is a rear elevation view thereof;

FIG. 3 is a left side elevation view thereof, the right side
elevation view being a mirror image thereof;

FIG. 4 is a top view thereof;

FIG. 5 is a bottom view thereof;

FIG. 6 is a front, right side, top perspective view thereof;

FIG. 7 is a rear, left side, top perspective view thereof;

FIG. 8 is an enlarged left side elevation view thereof;

FIG. 9 is a partial enlarged view of FIG. 6 thereof;

FIG. 10 is a partial enlarged view of FIG. 7 thereof;

FIG. 11 is a perspective view thereof in its intended envi-
ronment;

FIG. 12 is front elevation view of a rail for conveyor
machine showing our new design in accordance with a
second embodiment of the present invention;

FIG. 13 is a rear elevation view thereof;

FIG. 14 is a left side elevation view thereof, the right side
elevation view being a mirror image thereof;

FIG. 15 is a top view thereof;
